UNITED STATES PATENT OFFICE.

CHARLES H. GLADISH AND EDWIN B. GLADISH, OF HIGGINSVILLE, MISSOURI, AS
SIGNORS TO LEAHY MANUFACTURING CO., A CORPORATION OF MISSOURI.

INCUBATOR TRAY.

Application filed June 23, 1927. Serial No. 200,916.

The invention aims to provide a new and improved form of hatching tray for incubators, provided with novel means for turning the eggs, the construction being such that upon removal of a turning member from one portion of the egg-supporting means and insertion of said member into another portion thereof, the eggs of both portions will be turned by said removal and insertion operations.

With the foregoing in view, the invention resides in the novel subject matter herein-after described and claimed, the description being supplemented by the accompanying drawing.

Fig. 1 is a perspective view of an egg tray constructed in accordance with my invention.

Fig. 2 is a sectional view on line 2—2 of Fig. 1.

20 A tray is shown embodying a frame 3 and an egg-supporting screen 4, the tray herein disclosed being divided by a transverse partitioning strip 5 into two compartments of uniform size. At least one side of each compartment is formed with a longitudinal slot 6 and in the construction shown, these slots extend throughout the length of both the front and rear portions of the tray, so that either longitudinal edge of said tray 30 may face the front of the incubator, permitting insertion of the tray with less care than would be necessary if only one slot, to be located at the front of the incubator, were employed. In some instances, slots such as 6 35 may be provided at the ends of the tray instead of at its longitudinal sides. Hence, it is to be understood that by the language herein used, we comprehend this construction also, even though we may make reference to 40 a slot in a side of the tray, in a side of an egg-supporting portion, etc.

The numeral 7 denotes a T-shaped egg-turning member, preferably formed from two metal strips spot-welded or otherwise secured together, although wooden strips or strips of other desired materials, could be employed if desired. This egg-turning member lies slidably upon the egg-supporting screen or other surface 4 of one of the egg-containing compartments and its head 8 then is normally disposed at the side of the compartment remote from the slot 6 through which the shank 9 of said member passes. It will thus be seen that by outwardly pulling 55 the member 7 by means of its shank 9, the

head 8 of said member must pass under the eggs, thus effectively turning them. Then, the member 7 is inserted into the next egg-containing compartment through its slot 6 and upon this insertion, the eggs of this second compartment are also turned. The turning device 7 remains in this second compartment until the next turning of the eggs is required, whereupon it is removed and reinserted in the first compartment, thus effecting turning of the eggs of both of said compartments.

While a tray is shown embodying two egg-containing compartments, it will be understood that it might embody more or less. 70 Moreover, while in the present showing, the turning device 7 merely co-acts with one tray, it will be understood that this same turning device could be used for turning the eggs in a number of trays. The outer end of the shank 9 of this member is preferably bent upwardly to provide a handle 10 which assists in operating said member, and when said member is in its normal position, this handle may well lie closely against one side 75 of the tray so that it will not interfere with closing of the door of the incubator.

Excellent results are obtainable from the details disclosed and they are therefore preferably followed. However, within the scope 80 of the invention as claimed, variations may be made.

We claim:—

1. An incubator tray having a slot extending longitudinally of one of its side members, 90 and a T-shaped egg-turning member insertable and removable through said slot, said member being slideable upon the egg-supporting means of the tray, permitting its head portion to act as turning means for the eggs, the shank portion of said turning member being of substantially the same length as the dimension of the tray measured in the direction in which said shank portion extends.

2. Egg-supporting means for an incubator comprising two egg-containing portions of uniform size and each having a slot extending longitudinally of its front side member, and a T-shaped egg-turning member lying slidably upon the egg-supporting surface of one of said portions with its shank passing outwardly through the slot of the latter, the head of said member being normally disposed at the side of said one portion remote 105 110

from its slot, the egg-supporting surface of the other of said portions being entirely exposed, whereby upon withdrawal of said member through said slot, causing said head 5 to turn the eggs on said supporting surface of said one portion said member may be inserted through the slot of the other of said portions to turn the eggs of the latter.

3. An egg-turning device comprising a T-shaped member for insertion into a tray under the eggs, the head of said member consisting of a narrow strip constituting egg-turning means and the shank of said member forming an operating handle for said head 15 and being of a length corresponding to the

width of the egg tray in which it is to be used.

4. An incubator tray having an opening in its side wall and a T-shaped egg-turning member composed of narrow strips and slideable upon the egg-supporting means of the tray permitting its head to act as turning means for the eggs, the shank of said member corresponding in length to the width of the egg tray and being movable through the 20 opening in said side wall. 25

In testimony whereof we have hereunto affixed our signatures.

CHARLES H. GLADISH.
EDWIN B. GLADISH.
